UNITED STATES PATENT OFFICE

TREVOR R. GAUTIER, OF NASHUA, NEW HAMPSHIRE, ASSIGNOR TO NASHUA GUMMED AND COATED PAPER COMPANY, OF NASHUA, NEW HAMPSHIRE, A CORPORATION OF MASSACHUSETTS

COATING-APPLYING DEVICE

Application filed September 13, 1926. Serial No. 135,062.

My invention aims to provide improved means for moistening adhesive or gummed stickers, labels, sealing tape or strips, or other like adhesive material or for applying adhesive to similar but ungummed material.

In the accompanying drawings illustrating by way of example one form of the invention:

Fig. 1 is a side elevation of a moistening device embodying my invention; and

Fig. 2 is a vertical, longitudinal section thereof.

Referring more particularly to the drawings the illustrative device shown includes 15 a receptacle or container, such as the tank or reservoir 1, having a suitable base, herein including the lugs 2, 2, whereby the device may rest upon any suitable surface when it is to be used alone, or may be received in 20 strip serving apparatus of any desired type for use in conjunction therewith.

In the reservoir is an inverted wick, brush, or moistening element 3 having yieldable hairs or bristles of a length to project above 25 the reservoir while the lower portion of the brush is submerged in the liquid therein, whereby moisture will be conducted, by capillary action, to the exposed upper portion of the brush. The top of the reservoir includes a forward portion 4, and a rear portion 5 spaced sufficiently therefrom to permit the brush to project upwardly between their adjacent edges. The brush may be held in proper position in the reservoir, preferably 35 removably, and desirably at somewhat of an inclination to the vertical, by any suitable means, such as the opposed pairs of ribs 6, 6 on the inner side walls of the reservoir, cooperating with said portions 4 and 5. The 40 adjacent bottom portions of the reservoir may be inclined, as indicated at 6^a, to assist in positioning the brush.

The adhesive strip or tape to be moistened is guided in cooperative relation to the moistener or brush 3. Herein, for the purpose stated, the upper wall portion 5 of the reservoir provides a guide, the strip to be moistened passing between said guide and an overlying weight, presser, guide, platen, pressure member or bar, flap, or presser plate 7

the forward portion of which rests yieldably upon the upper portion of the brush 3. Said presser 7 is hingedly or pivotally supported or mounted for movement toward and away from the brush, as by means of the fingers 8 on said plate, having recessed lower edges so as to seat pivotally upon a bar or cross piece 9 on the reservoir and spaced from it sufficiently to permit passage of the strip to be moistened. By reason of said construction and arrangement of the presser and the cooperating brush, a moistening couple is provided which is effective to moisten the strip or tape thoroughly but offers but slight resistance to its passage, due to the ability of the presser, and of the hairs or bristles of the brush to yield. The described construction also permits the presser to adjust itself for wear of the brush or for variation in the positioning thereof in the reservoir 55 whereby the moistening couple is self adjusting and the pressure on the brush moistener, the hairs or bristles of which provide multiplex contact means, is kept substantially constant and adjusted to any possible irregularities in the thickness of the strip or tape, or to wear of or varying position of the brush. 60

The presser and reservoir are formed to insure proper reception and guiding of the adhesive material to be moistened up to and across the exposed bristles or hairs of the brush, and for this purpose the under surface of the presser and the adjacent upper guide surface of the reservoir are inclined, as indicated at 10, 11 respectively, whereby said surfaces are substantially parallel to the desired path of the strip or tape, which will be passed accurately to and between the presser and brush, the latter acting substantially as a continuation of said guide. Said presser is formed and proportioned to afford proper and uniform moistening contact of the strip or tape and the brush, the presser being suitably weighted, if desired, as indicated at 12. 65 As above mentioned, however, the presser is readily yieldable upwardly, or away from, the brush, permitting easy passage of the strip or tape. 70

It will be noted that the presser may with 75 ease be lifted to afford access to the brush, 80

or may equally readily be bodily removed for cleaning or inspection purposes. To assist in proper positioning of the presser with respect to the brush when the presser is lowered or replaced after such lifting or removal, or at other times, or to prevent excessive pressure on the moistener I may provide suitable means such as the stops or screws 13, 13 adjustable by increments of any desired extent, including extremely fine adjustments, in the respective ears 14 on the reservoir. Said adjustable stops underlie the presser so as to prevent undue downward movement thereof, and serve to govern its angular position.

The cover or top of the reservoir may be either removable or integral as desired, and filling means such as the lip 15 and cooperating opening in the adjacent wall of the reservoir may be provided, said lip, as illustrated, also providing a convenient means for grasping the reservoir for removing it from its position in a strip serving apparatus.

My invention is not limited to the particular embodiment thereof herein shown and described, its scope being set forth in the appended claims.

Claims:

1. Mechanism for moistening adhesive or gummed strips, tapes, labels or the like comprising a reservoir, a brush moistener in said reservoir, a plate or guide to direct the material to be moistened to and across the brush in moistening contact with the projecting bristles thereof, said plate or guide having a pivotal support permitting it to yield away from the brush and to be lifted for cleaning or inspection purposes, and a plate-engaging member on the reservoir, having threaded engagement with a portion thereof whereby said member is vertically adjustable with respect to the reservoir by increments of any desired extent, including extremely fine increments, said member underlying said plate properly and positively to position the same when it is lowered or replaced after lifting or removal or to prevent undue pressure of said plate upon the brush.

2. In a device for applying a liquid coating to strip material, a reservoir for the liquid, a brush in the reservoir with the free ends of its hairs or bristles projecting above the liquid level, a presser plate having a portion overlying the brush, a stationary strip or bar extending transversely of the path of the strip material and above the reservoir, said strip or bar having its upper edge formed to constitute a fulcrum, and means on the presser plate provided with a downwardly-opening formation for receiving said upper edge of said strip or bar in a manner permitting vertical pivotal movement of the plate and also permitting complete bodily removal thereof at any time.

3. Means for moistening a gummed paper

strip and adapted for use alone or in conjunction with strip serving mechanism, comprising, in combination, a liquid receptacle 1 having a base upon which it is adapted to stand upright, a brush 3 set in the receptacle 70 with the free ends of its hairs or bristles projecting above the highest liquid level, supporting means 6, 6 in the receptacle for removably holding the brush in said position, guide means 5, 11 on the receptacle for cooperation with the under face of the strip to conduct the latter to and upwardly across the projecting end of the brush, a downwardly-pressing platen 7 overlying said guide means and brush and cooperating therewith to conduct the strip in moistening relation with the brush, a cross-piece 9 associated with the reservoir, spaced rearwardly from the projecting portion of the brush and arranged to permit the strip to be passed beneath the 85 cross-piece, one or more rearwardly extending fingers 8 having downwardly-open bearing recesses adapted to be engaged with said cross-piece 9 whereby the latter provides a pivotal support for the platen 7 while enabling the platen to be removed bodily from its operative position without manipulation of other parts, and means 13, 14 for adjusting the platen relatively to the brush.

In testimony whereof, I have signed my name to this specification.

TREVOR R. GAUTIER.
